UNITED STATES PATENT OFFICE.

BRYSON D. HORTON, OF DETROIT, MICHIGAN.

CENTER STOP AND OUTSIDE LOCK-OFF FOR ELECTRICAL SWITCHES.

1,383,541.

Specification of Letters Patent.

Patented July 5, 1921.

Application filed June 26, 1918. Serial No. 241,945.

To all whom it may concern:

Be it known that I, BRYSON D. HORTON, a citizen of the United States, residing at Detroit, county of Wayne, and State of Michigan, have invented certain new and useful Improvements in Center Stops and Outside Lock-Offs for Electrical Switches, of which the following is a full, clear, and concise description.

10 My invention relates to center stop and outside lock off mechanism for electrical switches and is particularly related to inclosed electrical switches.

One of the objects of this invention is to 15 design a device of the above character which may be readily attached to the outside of the casing of an inclosed electrical switch.

A further object of this device is to design 20 a center stop which will temporarily retain a double throw switch in central or neutral position.

A further object of this device is to provide 25 means whereby in a double throw switch a rapid continuous motion from one extreme limit of its stroke to the other is assured and that all other motions are normally prevented.

A further object of this invention is to provide 30 a center stop which though temporarily retaining the double throw switch in neutral position may be readily manually released.

A further object of this invention is to so 35 design a device that it is adapted to operate as an outside lock off to permanently lock a switch in off position when so desired.

A further object of this invention is to design 40 a device which incorporates in one structure all the functions enumerated above.

45 A further object of this invention is to design a very simple and practically fool proof structure which is sure in its operation and of a very rugged character.

One of the many possible forms which this 45 invention may take is shown in the accompanying drawings in which—

Figure 1 shows a side view of a double throw quick break switch and casing with the center stop and outside lock off shown in 50 engagement with the operating member of the switch. Fig. 2 shows a plan view of the outside lock off and center stop in the position shown in Fig. 1 and shows in dotted lines a portion of the locking member out

of engagement and also turned completely 55 out of the way of the operating member of the switch.

Referring in detail to the drawings 1 indicates the casing of the electrical switch to which applicant's center stop and lock off is 60 attached. The switch is operated by means of an operating member 2 which is pivotally mounted in the casing and the switch mechanism includes stationary contacts 3 and movable contacts 4, and is of the double throw 65 quick break type. This switch is similar in all respects to the switch described and shown in application Serial No. 242,081, filed by me on June 17, 1918. Only so much of the switch is shown here as would indicate that this switch is of the double throw 70 quick break type.

The center stop and outside lock off mechanism comprises a fixed plate 5, which is fastened by means of screws or other suitable fastening means 6 to the exterior of the casing. This fixed plate has hingedly connected thereto a movable plate 7. The hinged mechanism is shown at 16. This movable plate 7 is held down by means of 75 suitable springs 9 which are fastened at their lower end to the casing as shown, or may be fastened to the fixed plate 5. The upper ends of these springs are fastened to the movable plate 7 and serve to hold such 80 movable plate 7 down in engagement with the stop 10. This movable plate 7 is provided with a central notch 8 adapted to receive the operating member 2 when in 85 neutral position, as shown in full lines in 90 Fig. 1.

Attention is called to the fact that the dotted lines in Fig. 1 show the switch out of neutral position and occupying an intermediate position between neutral and one of 95 its closed positions.

Pivotally mounted on the movable plate 7 is a locking member 11, which is provided with a plurality of openings 12 which are aligned with similar openings 13 on the movable plate 7, when this locking means is in a position shown in full lines in Fig. 2. When these openings are in alignment they are adapted to receive the bail portion of a padlock or similar locking means, and it will 100 105 be seen that the notch 14 in this auxiliary member 11 aligns with the notch 8 in the movable plate 7 and serves to lock the

movable plate 7 in engagement with the operating member 2 of the switch, when this device functions as an outside lock off. When this auxiliary member is not in use, it is turned around in the position shown in dotted lines in Fig. 2, the notch 14 then alines with the opening 15 in the movable plate 7, and the padlock may then be passed through such opening 15 and notch 14 and retain this member out of the path of movement of the operating member of the switch. However, the frictional engagement between the plate 7 and the auxiliary member 11 may be such that this locking of the auxiliary member in inactive position will not be necessary.

The operation of this device is as follows:—

When it is functioning as a center stop for the double throw switch which is desirable in quick break double throw switches, the operating member 2 of the switch lifts the plate 7 upwardly until it comes adjacent the notch 8 whereupon the plate 7 snaps downwardly through the action of the springs 9 and retains this operating member 2 in neutral position, as shown in Fig. 1.

This device is also capable and designed to operate as a means of insuring a quick continuous motion of the switch from one extreme limit to the other extreme limit as for example is necessary in certain types of electrical work, such as motor starting. Under this condition when the operating member 2 is rapidly moved from one extreme position toward the other extreme position it suddenly raises the plate 7 and the momentum thereby acquired by the plate 7 serves to hold the notch 8 out of the path of motion of the operating member 2 during the brief period of its passage by such notch 8. Should, however, the operator inadvertently attempt to move the switch slowly from one position to the other position, the movable member 7 would immediately snap downward when the notch 8 comes into engagement with the operating member 2 and would thereby arrest the motion of the switch.

When this device functions as a lock off, the member 11 is rocked about its pivotal point around in the position shown in Fig. 2 and a suitable padlock or other means serves to lock this auxiliary member 11 to the movable member 7 and thereby locks such a movable member 7 in engagement with the operating member 2 and locks the switch in neutral position.

It will readily be seen from the above that applicant has provided a very simple device which has a number of desirable functions, such as enumerated above, and that this device when operating as a center stop may be readily manually released thereafter allowing the switch to be operated as desired.

I claim:—

1. The combination with a double throw quick break switch of a center stop therefore comprising a fixed plate and a movable notched plate mounted thereon to swing about an axis in substantially the plane of the first plate and a spring for actuating said notched plate. 70

2. The combination with a double throw incased switch having stationary and movable parts of an outside lock off comprising a plate fixed to the casing of said switch, a notched plate hingedly mounted thereon, and means pivotally mounted on said notched plate and adapted to lock said notched plate in engagement with a portion of the movable part of said switch when in neutral position. 75

3. A center stop for double throw switches having an operating member, comprising a fixed plate, a movable notched plate mounted thereon to swing about an axis in substantially the plane of the first plate, and means tending to normally place said notched plate in a definite position. 85

4. A center stop for double throw switches having an operating member, comprising a fixed plate, a movable notched plate mounted thereon to swing about an axis in substantially the plane of the first plate, and a plate mounted on the notched plate for closing the notch. 90

5. A center stop for double throw switches having an operating member, comprising a fixed plate, a movable notched plate mounted thereon to swing about an axis in substantially the plane of the first plate, and a plate mounted on the notched plate for closing the notch, said two movable plates having alining openings whereby the operating member may be locked in the notch. 100

6. The combination with the wall of a switch inclosure and switch operating member projecting through said wall and mounted to oscillate about an axis perpendicular thereto, a portion of said member being at right angles to its axis, of a center stop for said member comprising two plates hinged together, one plate being fastened to the wall and the other normally projecting perpendicularly to the wall, said last mentioned plate having a notch engageable with the portion of the operating member. 110

7. The combination with the wall of a switch inclosure and switch operating member projecting through said wall and mounted to oscillate about an axis perpendicular thereto, a portion of said member being at right angles to its axis, of a center stop for said member comprising two plates hinged together, one plate being fastened to the wall and the other normally projecting perpendicularly to the wall, said last mentioned plate having a notch engageable with the portion of the operating member, and a plate 120

115

125

130

mounted on the notched plate for closing the notch.

8. The combination with the wall of a switch inclosure and switch operating member projecting through said wall and mounted to oscillate about an axis perpendicular thereto, a portion of said member being at right angles to its axis, of a center stop for said member comprising two plates hinged together, one plate being fastened to the wall and the other normally projecting perpendicularly to the wall, said last mentioned plate having a notch engageable with the portion of the operating member, and a plate mounted on the notched plate for closing the notch, said two movable plates

having alined openings whereby the operating member may be locked in the notch.

9. The combination with the wall of a switch inclosure and switch operating member projecting through said wall and mounted to oscillate about an axis perpendicular thereto, a portion of said member being at right angles to its axis, of a center stop for said member comprising two plates hinged together, one plate being fastened to the wall and the other normally projecting perpendicularly to the wall, said last mentioned plate having a notch engageable with the portion of the operating member, and yielding means to hold the plate in such position.

BRYSON D. HORTON.
